US00D827694S

(12) **United States Design Patent** (10) Patent No.: **US D827,694 S**
 (45) Date of Patent: **** Sep. 4, 2018**

(54) **REFLECTOR FOR PHOTOGRAPHY OR CINEMATOGRAPHY**

(71) Applicant: **CARBON SYSTEM VERWALTUNGS GMBH, Marktheidenfeld (DE)**

(72) Inventor: **Markus Kreuzer, Marktheidenfeld (DE)**

(**) Term: **15 Years**

(21) Appl. No.: **35/503,277**

(22) Filed: **Jun. 6, 2017**

(80) **Hague Agreement Data**

Int. Filing Date: **Jun. 6, 2017**

Int. Reg. No.: **DM/096575**

Int. Reg. Date: **Jun. 6, 2017**

Int. Reg. Pub. Date: **Jul. 7, 2017**

(51) LOC (11) Cl. **16-05**

(52) U.S. Cl.

USPC **D16/237; D16/241**

(58) **Field of Classification Search**

USPC **D16/229-241; D10/20, 39**

CPC **A47F 1/00; A47F 9/00; A47F 7/283**
